Filed March 31, 1932

Inventor:

Alexander H. Masters.

UNITED STATES PATENT OFFICE

ALEXANDER H. MASTERS, OF GREENSBORO, NORTH CAROLINA

DESIGN FOR A COMBINATION ASH TRAY AND CIGAR LIGHTER

Application filed March 31, 1932. Serial No. 43,340. Term of patent 7 years.

To all whom it may concern:

Be it known that I, ALEXANDER H. MASTERS, a citizen of the United States, residing at Greensboro, in the county of Guilford and State of North Carolina, have invented a new, original, and ornamental Design for a Combination Ash Tray and Cigar Lighter, of which the following is a specification, reference being had to the accompanying drawing, forming part thereof.

The figure is a front perspective view of a combination ash tray and cigar lighter showing my new design. The rear of the article appears as a plain board wall.

I claim:

The ornamental design for a combination ash tray and cigar lighter as shown and described.

ALEXANDER H. MASTERS.
